UNITED STATES PATENT OFFICE.

WALLACE BRUCE, OF POUGHKEEPSIE, NEW YORK.

DESIGN FOR A PANORAMA OR MAP CASE.

SPECIFICATION forming part of Design No. 16,540, dated February 23, 1886.

Application filed October 23, 1885. Serial No. 180,770. Term of patent 7 years.

To all whom it may concern:

Be it known that I, WALLACE BRUCE, of Poughkeepsie, in the county of Dutchess and State of New York, have produced a new and original Design for a Panorama and Map Case, of which the following is a specification.

Reference is to be had to the accompanying drawing, forming a part of this specification, in which the figure is a perspective view of my newly-designed panorama-case.

The leading feature of my design consists of a bulging cylindrical case flat at its ends, surrounded with annular ribs or bands, and showing at one portion two parallel longitudinal lines reaching nearly to the ends of the case, the said parallel lines being divided intermediate of their lengths by the circular protuberance.

The panorama-case A is flat and circular at its ends $a a'$, and is of greater diameter in its center than at its ends, and the outlines $b b'$ from end to end of the case are in slight opposite curves having the same radii. Near the end a the case is surrounded by two annular ribs or bands, $c c'$, and near the end a' the case is surrounded by two similar bands, $d d'$. Two other annular ribs or bands, $e e'$, surround the case near to, equidistant from, and on opposite sides of the center of the case.

Upon one side of the case A appear two parallel lines, $f f$. These are longitudinal to and reach nearly the whole length of the case, and are joined at their ends by straight lines $f' f'$ at right angle to the lines $f f$, and at the center of the case, the lines $f f$ are broken with two corresponding semicircular lines, $g g$, that curve in opposite directions, and from these semicircular lines $g g$ appears a circular protuberance, h , standing out from the center of the case, so that the case presents to the eye the effect of a keg or barrel with flat heads and a bung.

Having thus described my invention, I claim as new and desire to secure by Letters Patent—

The design for a panorama and map case herein shown and described, the same consisting of the flat circular heads $a a'$ and a cylindrical bulging body having surrounding annular ribs or bands, and showing two parallel lines, $f f$, opposite semicircles $g g$, and cylindrical protuberance h , projecting from the semicircles $g g$.

WALLACE BRUCE.
